UNITED STATES PATENT OFFICE.

ALFRED A. BINDEL, OF RACINE, WISCONSIN.

WRENCH.

1,250,082.

Specification of Letters Patent. Patented Dec. 11, 1917.

Application filed March 17, 1917. Serial No. 155,596.

To all whom it may concern:

Be it known that I, ALFRED A. BINDEL, a citizen of the United States, residing at Racine, in the county of Racine and State of Wisconsin, have invented new and useful Improvements in Wrenches, of which the following is a specification.

This invention comprehends improvements in wrenches and relates more particularly to a monkey wrench having a fixed jaw and a slidable jaw, which is connected to and movable by a carriage having a cam or eccentric lever for tightening the movable jaw against a nut.

Another object of the invention is to provide a simple and practical wrench of this type which may be easily and quickly assembled, which is substantial and practical and which may be cheaply manufactured.

With these and other objects in view as will become more apparent as the description proceeds, the invention consists in certain novel features of construction, combination and arrangement of parts as will be hereinafter fully described, illustrated and claimed.

In the drawings,

Figure 1 is a side elevation of the wrench.

Fig. 2 is a longitudinal sectional view therethrough.

Fig. 3 is a transverse sectional view on the plane of line 3—3 of Fig. 1.

Fig. 4 is a sectional view on the plane of line 4—4 of Fig. 1.

Fig. 5 is a detail perspective view of the sliding jaw.

Fig. 6 is a perspective view of the carriage.

Referring in detail to the drawings by numerals, 1 designates the shank of the wrench having a fixed jaw 2 on one end thereof and a handle 3 on the other end thereof, said handle being secured against the head 4 by the nut 5. The head 4 is formed with a longitudinal opening through which the shank extends and is secured to the shank by a rivet 6. Forwardly facing teeth 7 are formed on one edge of the shank between the fixed jaw 2 and the head 4, and longitudinal channels 8 are formed in the sides of the shank.

A movable jaw 9 having a shank opening 10 is slidable on the shank and is formed on its rear side adjacent the side edges of the shank opening 10 with a pair of laterally and rearwardly extending arms 11 having

outwardly projecting heads or flanges 12 on their rear ends. The arms and heads lie entirely on the outer sides of the plates of the side walls of the shank opening 10 so that the movable jaw may be easily slipped on to the shank before the head 4 and handle 3 are positioned.

A carriage 13 having a shank opening 14 is slidably mounted on the shank and is provided with a cam or eccentric lever 15 pivotally secured between the carriage ears 16 by a pivot or other suitable fastener 17. A spring rack 18 having rearwardly facing teeth 19 is secured adjacent one end within the shank opening 14 to the top wall thereof by screws or other suitable fasteners 20 and said teeth 19 are normally held in engagement with the teeth 7 by a flat spring 21 preferably mounted on the bottom wall of the shank opening 14 for engagement with the shank 1. The side walls 22 of the carriage are formed with the slots or openings 22' intermediate their ends and the unslotted portions 23 are formed on their opposed faces with grooves or channels 23' through which the arms 11 slide.

In assembling the wrench, the slidable jaw is first slipped on the shank 1, then the carriage is positioned and by springing the arms 11 into the channels 8 of the shank, their heads 12 may be moved into the position shown in Fig. 1. The head 4 and handle 3 are then secured in position, after which the wrench is ready for use.

The spring 21 is a comparatively weak member, embodying sufficient strength, however, to move the carriage 22 transverse of the shank 1, so that the teeth of the rack bar will be brought to engage with the teeth of the shank. The normal engagement between the rack bar and the teeth 7 of the shank 1 is desirable, for the reason that the wrench may be held at any desired angle before the final adjustment between the jaws of the wrench is made. A slight pressure against the carriage, by the operator from the portion thereof to which the spring 21 is secured, will cause a movement of the said carriage to bring the teeth of the rack bar out of engagement with the teeth 7 of the shank, permitting the manual adjustment in a longitudinal direction of the carriage, and, of course, of the slidable jaw 9 carried by the carriage. When such adjustment is made and the article to be gripped is arranged between the jaws 2 and

9, the lever 15 is swung upon its pivot 17 bringing its cam head into contacting engagement with the spring rack 18, forcing the teeth of the latter in engagement with the teeth 7 of the shank 1, the said cam head also contacting with the rear face of the jaw 9, moving the same longitudinally outward of the carriage and in the direction of the stationary jaw 2, thus effecting a firmer grip upon the article between the jaws 2 and 9. The arrangement of the arms 11 permits a free limited longitudinal movement of the jaw 9 with respect to the carriage 13, the flange or offset ends 12 of the said arms, however, being arranged to contact with the outer unslotted portion 23 of the carriage limits the outward movement of the jaw 9 with respect to the carriage, while the contacting engagement of the jaw 9 with one of the ends of the carriage will, of course, limit the inward movement of the said jaw 9 with respect to the carriage 13.

What I claim is:—

1. A wrench including a fixed jaw having a toothed shank, a carriage slidable on said shank, a spring toothed rack carried by the carriage, spring means between the carriage and shank for normally sliding the carriage laterally of the shank to bring the toothed rack to engage with the teeth of the shank, a movable jaw on the shank, means between said movable jaw and the carriage for associating the said jaw to the carriage to permit of the limited longitudinal move-

ment of the movable jaw with respect to the carriage, and a pivoted lever having a cam head on the carriage and designed, when the said lever is swung in one direction, to contact with the spring rack to force the same into engagement with the teeth of the shank and to also contact with the inner face of the movable jaw to force the latter in the direction of the stationary jaw.

2. A wrench including a stationary jaw having an angular toothed shank, a carriage slidable on said shank, a spring rack having one of its ends secured to said carriage, a slight spring connected to the carriage and designed to slide the carriage laterally of the shank to bring the teeth of the rack in engagement with the teeth of the shank, a slidable jaw on the shank outward of the carriage, angularly extending arms upon said jaw received in depressions in the carriage, said arms having angular ends, whereby to limit the slidable movement of the said jaw with respect to the carriage, a cam lever pivoted to the carriage outward of the spring rack, said lever, designed, when swung in one direction, to engage with the rack to force the same in tight engagement with the teeth of the shank, and to also engage with the inner face of the slidable jaw to move the same outwardly of the carriage toward the stationary jaw.

In testimony whereof I affix my signature.

ALFRED A. BINDEL.
